(57) **CLAIM**

The ornamental design for a high heeled shoe sole, as shown and described.

DESCRIPTION

FIG. 1 is a perspective view of a high heeled shoe sole showing my new design;

FIG. 2 is a bottom plan view thereof;

FIG. 3 is a right side elevational view thereof;

FIG. 4 is a left side elevational view thereof;

FIG. 5 is a rear elevational view thereof; and,

FIG. 6 is a front elevational view thereof.

The broken line showing of a shoe mid-sole, a shoe upper, a brand logo tag, an attachment material for attaching the sole portions of a shoe, and tread patterns on a shoe in FIGS. 1–6 is included for the purpose of illustrating only and forms no part of the claimed design.

1 Claim, 6 Drawing Sheets
